UNITED STATES PATENT OFFICE.

JOSEPH ICHER, OF SAGAMORE, PENNSYLVANIA.

SCREEN DOOR.

Application filed October 22, 1921. Serial No. 509,485.

To all whom it may concern:

Be it known that I, JOSEPH ICHER, a citizen of the United States, residing at Sagamore, in the county of Armstrong and State 5 of Pennsylvania, have invented certain new and useful Improvements in Screen Doors, of which the following is a specification, reference being had to the accompanying drawings.

10 This invention relates to screen doors and has for its object the provision of a screen door structure including swinging screen doors proper permanently hinged within a frame adapted to be applied bodily to a 15 doorway, the advantage being that the screen doors proper and their supporting frame are a complete and separate entity which may be manufactured and sold as such for ready application to a doorway and which 20 may be secured in position merely by a plurality of nails or screws which hold the frame upon the door frame, it being thus unnecessary for the user to have to cut, fit and hang the doors as is necessary in the 25 use of the ordinary well known screen door.

An important object is the provision of a device of this character in which the permanent frame of the screen doors proper is capable of being folded so that when the 30 use of the structure is not desired and it is removed from the doorway it may be folded for storage in a small space or for convenience in transportation.

A further object is the provision of a 35 structure of this character which includes two screen doors proper which have connecting means whereby they will both be opened when one is pushed against or pulled upon.

40 An additional object is the provision of a device of this character which will be simple and inexpensive in manufacture, highly efficient in use, durable in service and a general improvement in the art.

45 With the above and other objects and advantages in view, the invention consists in the details of construction to be hereinafter more fully described and claimed, and illustrated in the accompanying drawings, in 50 which:

Figure 1 is an elevation of my device in applied position;

55 Figure 2 is a cross sectional view therethrough on the line 2-2 of Figure 1 showing it in applied position; and

Figure 3 is a plan view.

Referring more particularly to the drawings, the letter A designates the usual frame of a doorway in a building. Ordinarily screen doors are applied to such a frame 60 by hinging them directly upon one side and providing an abutment strip at the other side or else by nailing strips to the frame and hinging the screen door proper upon said strips. These old and well known 65 methods of application have the great disadvantage of requiring considerable skill in properly hanging the door and they have the additional disadvantage of seriously marring the wood work so as to leave it more 70 or less unsightly after the screen door is taken down.

In carrying out the present invention which eliminates the above mentioned disadvantages, I make use of a frame including 75 upright sides 10 to the upper ends of which is suitably secured a cross member 11 which is formed in sections hingedly connected, as indicated at 12. Disposed within the opening in the frame is a pair of screen 80 doors proper, indicated at 13, and formed of suitable frames covered with wire screen in the usual manner, these doors being hinged upon the uprights 10, as shown at 14, and it will be apparent that these hinges 85 may be of the type which will permit the doors 13 to swing in only one direction or in both directions, this detail not forming an essential part of the invention.

Connected with the upper outer corners 90 of the doors 13 are the horizontal arms 15 of rods 16 which are journaled in suitable bearings 17 and which are formed between said bearings with crank portions 18. Pivoted transversely at the center of the cross 95 member 11 is a rocker arm 19 with the ends of which are pivotally connected links 20 which are in turn pivotally connected with the crank portions 18. It is also preferable to provide a coil spring 21 connected with 100 one of the crank portions and with a stud or the like projecting from the cross member 11 for the purpose of normally holding the doors 13 in closed position.

When the door is manufactured and assembled it is intended that it may be shipped in folded position, that is with the cross bar 11 folded back upon itself on the hinges 12 and with the doors 13 arranged one upon the other. This folding is not illustrated 110 in the drawings as it is so obvious how it is effected. In applying the door it is of

course necessary that it be unfolded so that the cross bar 11 will have both sections arranged in the same plane with the doors 13 likewise arranged in the same plane. The 5 frame is then placed in position against the frame A of the doorway and secured by means of securing members 22 which pass through the uprights 10 and into the sides of the door frame A, these securing members 10 being preferably screws and the holes therefor being initially provided in the uprights 10 so as to relieve the user of the necessity of ascertaining the exact points where the securing members should be 15 placed. When the door is thus applied and the link and rocker arm connection assembled it will be apparent that when one door 13 is pushed or pulled open it will result in rotation of the associated rod 16 and 20 crank portion 18 and owing to the connection of the two crank portions with the central rocker arm 19 it will be apparent that the other door will be correspondingly swung. In this way simultaneous opening and closing 25 of both doors is effected. As above mentioned, the spring 21 always operates to resist opening movement and serves to effect closing after the doors have been opened. When the use of the structure is no longer 30 desired it is apparent that the securing members 22 may be readily moved whereupon the frame and the doors mounted therein may be removed bodily and the only defacing 35 of the door frame A will be the holes left when the screws 22 are removed.

From the foregoing description and a study of the drawings it will be apparent that I have thus provided a very simply

constructed and consequently inexpensive screen door structure which may be applied 40 and secured in position by even a most unskilled person in a very few minutes' time and without the employment of any tools other than a screw driver. Owing to this particular arrangement it is apparent that 45 the doors being permanently associated with the frame will always hang properly and will present a very neat and attractive appearance.

While I have shown and described the 50 preferred embodiment of the invention it is of course to be readily understood that I reserve the right to make such changes in the form, construction and arrangement of parts as will not depart from the spirit 55 of the invention or the scope of the subjoined claim.

Having thus described my invention, I claim:

A door structure of the character described comprising a permanent frame adapted to be secured upon the door frame of a building, a pair of doors proper hinged within said frame, rods mounted at the upper outer corners of the doors proper and including horizontal portions secured thereto and vertical portions journaled upon the frame, said vertical portions being formed with cranks, a rocker arm pivoted centrally upon the top of the frame, and links pivotally connected with the rocker arm and with said cranks. 70

In testimony whereof I hereunto affix my signature.

JOSEPH ICHER.
